UNITED STATES PATENT OFFICE.

GEORGE G. FLOYD, OF CHICAGO, ILLINOIS, ASSIGNOR TO AMERICAN STEEL FOUNDRIES,
OF CHICAGO, ILLINOIS, A CORPORATION OF NEW JERSEY.

SIX-WHEEL TRUCK.

1,418,294.

Specification of Letters Patent. Patented June 6, 1922.

Application filed January 30, 1922. Serial No. 532,577.

To all whom it may concern:

Be it known that I, GEORGE G. FLOYD, a citizen of the United States, residing at Chicago, in the county of Cook and State 5 of Illinois, have invented certain new and useful Improvements in Six-Wheel Trucks, of which the following is a specification.

This invention relates to six-wheel railway car trucks.

It has been found in various types of six-wheel car trucks that there is a tendency for the middle journal box to tilt an amount which is permitted by the clearance between the journal box and the jaws. Such jaws 15 have been formed integrally with the side frame, in which case it has been necessary to allow a certain amount of clearance to permit a free vertical movement of the middle pair of wheels. The tilting action 20 has been due primarily to the fact that the inner ends of the equalizing levers which rest upon the intermediate journal box engage the latter six or eight inches above the center of the pivot points or the center of 25 the journal and also have an eccentric bearing relative to the center line, the resultant tendency being a tilting of the box. It is true that the jaws of the pedestal of the ordinary six-wheel truck prevent the box 30 tilting excessively. However, the box does tip or lean over an amount which the clearance permits. This tilting of the middle journal box has proved to be a serious problem in that the engaging portions of the 35 journal box and pedestal jaws wear excessively, thereby increasing the clearance and accordingly increasing the tilting of the intermediate journal box. This results in the middle axle moving out of parallelism 40 with the other axles, which in turn results in wear of the flanges of the wheels and of the rails.

Accordingly, one object of the invention is to provide a six-wheel truck arrangement in 45 which the intermediate journal boxes are positively held against any tilting action and at the same time permitted to have all necessary flexibility in the truck.

Another object is to provide a simple six- 50 wheel truck arrangement wherein the intermediate journal boxes are guided in a manner to meet all the requirements for successful commercial operation.

These and other objects are accomplished 55 by means of the arrangement disclosed on

the accompanying sheets of drawings, in which—

Figure 1 is a fragmentary top plan view of a railway car truck embodying my invention; 60

Figure 2 is a fragmentary side elevation of the same arrangement;

Figure 3 is a side elevation of a side frame of the six-wheel truck;

Figures 4 and 5 are side elevations of 65 equalizing levers embodying my invention;

Figure 6 is a detail sectional view taken in the plane of line 6—6 of Figure 2; and

Figure 7 is a detail sectional view taken in the plane of line 7—7 of Figure 2. 70

The various novel features of the invention will be apparent from the following description and drawings and will be particularly pointed out in the appended claims.

Referring to the figures of the drawings, 75 it will be noted that my invention is disclosed in connection with a six-wheel railway car truck including an integrally formed side frame 10 having journal box

openings 11 for the reception of end journal boxes 12, and also provided with openings 13 for the reception of end portions of bolster members 14. Equalizing levers 15 and 16 transmit a proper proportion of the load from the bolster members 14 to the intermediate journal boxes 17. In this particular instance the equalizing levers are in the 80 form of trusses in that they have tension members 18 and 19 respectively, and compression members 20 and 21 respectively. 90

These equalizing levers are made in the form of a truss for the purpose of securing sufficient strength in the case where vertical clearance space is limited. For example, when equalizing levers are in the form of 95 single bent beams the section receiving the load from the bolsters must be of considerable depth. Such depth would not permit of the proper clearance, especially where springs are interposed between the bolster 100 ends and the equalizing lever. However, by providing equalizing levers in the form of a truss the depth of the section of the tension member under the points of application of the bolster load may be greatly reduced to 105

meet the clearance conditions. The outer end of the equalizing lever 15 is pivotally connected to the side frame 10 adjacent and 110

inwardly from one of the end journal boxes 12 and between the side walls of the side frame

by means of a pivot pin 22. Likewise, the associated equalizing lever 16 is pivoted to the side frame adjacent the other end journal box 12 on the same side of the truck by a pivot pin 23.

As stated above, it has been found necessary to provide some means for preventing any tilting of the intermediate journal boxes on a six-wheel truck. To this end I have 10 provided the inner end of the equalizing lever 15 with integrally formed pedestal jaws 24 forming an opening 25 for the intermediate journal box 17. These jaws rigidly engage the intermediate journal box 15 and in effect provide no clearance therebetween. The effect is the same as having the intermediate journal boxes formed integrally with the inner ends of the equalizing levers 15. In this way the intermediate 20 journal boxes are positively held against any tilting action, and at the same time the intermediate axle is permitted to rise and fall with the pivotal action of the equalizing levers 15 as occasion demands due to track 25 irregularities.

Referring particularly to Figure 6, it will be noted that the inner end of the equalizing lever 15 is provided with side walls 26 forming a channel shaped pocket with a floor 30 portion 27 for the reception of the inner projecting end 28 of the associated equalizing lever 16. This projection 28 at the inner end of the equalizing lever 16 is provided with a wearing plate 29 which rests upon the 35 bottom or web portion 27 of the equalizing lever 15. The arrangement in effect is telescopic and pressure resulting from the loads from the bolster members 14 is exerted upon the middle of the intermediate journal 40 boxes. Also the equalizing levers 15 and 16 are held in proper relation with respect to each other as a result of their pivot connections at the outer ends and telescopic arrangement at the inner ends. The upper 45 parts or the compression members 20 and 21 of the equalizing levers 15 and 16 respectively are located up between the side walls 30 of the side frame 10 thereby limiting the amount of relative lateral movement between such parts and at the same time facilitating vertical clearance conditions.

By means of this arrangement a six-wheel truck is provided adapted to meet the various requirements for successful commercial 55 operation.

It is my intention to cover all modifications of the invention falling within the spirit and scope of the following claims.

I claim:

1. In a six-wheel car truck, the combination of a side frame, an intermediate journal box, an equalizing lever pivotally connected to said side frame and having pedestal jaws for receiving said intermediate journal box for preventing tilting of the latter. 60

2. In a six-wheel car truck, the combination of a side frame, an intermediate journal box, and an equalizing lever operatively connected to said side frame and having a portion for embracing said intermediate journal 70 box to prevent tilting of the latter.

3. In a six-wheel car truck, the combination of a side frame, an intermediate journal box, and a plurality of equalizing levers operatively associated with said side frame 75 and engaging each other at said intermediate journal box, one of said equalizing levers having an opening for receiving said intermediate journal box to prevent tilting of the latter. 80

4. In a six-wheel car truck, the combination of a side frame, an intermediate journal box, equalizing levers operatively associated with said side frame and having their inner ends telescopically arranged at said intermediate journal box, one of said equalizing levers having pedestal jaws for embracing said intermediate journal box to prevent tilting of the latter. 85

5. In a six-wheel car truck, the combination of a side frame, an intermediate journal box, and an equalizing lever in the form of a truss operatively connected to said side frame and having an opening for receiving said journal box for preventing tilting of 95 the latter.

6. In a six-wheel car truck, the combination of a side frame, an intermediate journal box, a plurality of equalizing levers pivotally connected to said side frame, bolster members operatively associated with said equalizing levers through which loads are transmitted to said intermediate journal box, one of said equalizing levers being provided with pedestal jaws for embracing said intermediate journal box for preventing tilting of the latter. 100

Signed at Chicago, Illinois, this 24th day of January, 1922.

GEORGE G. FLOYD.
